LINING ATTACHMENT FOR BEVELING MACHINES

Vernon E. Royle, Paterson, N. J.

Application January 29, 1937, Serial No. 122,938

15 Claims. (Cl. 29—21)

My invention relates to lining attachments for beveling machines, and more particularly to the cutter and cutter arm, with the object in view of providing simple and effective means for grooving 5 the edges of half-tone plates or other engravings—to cause them to print a plurality of marginal lines of equal or different widths and at any desired distance apart.

Another object of my invention is to provide 10 means for accurately establishing a predetermined width of groove cut in the plate with respect to the depth of the groove.

Another object is to provide a cutter having 15 a wide range of operations and which may be controlled to cut grooves of various widths and depths.

Another object is to provide certain improvements in the form, construction and arrangement of the several parts whereby the above 20 named and other objects may effectively be attained.

A practical embodiment of my invention is represented in the accompanying drawings, in which

25 Fig. 1 represents a plan view of my improved lining attachment and so much of a beveling machine as is necessary to show its operation in connection therewith;

Fig. 2 represents a vertical section, on an enlarged scale, taken in the plane of the line II—II of Fig. 1, looking in the direction of the arrows, and showing the means for laterally adjusting the cutter arm and adjacent mechanism;

30 Fig. 3 represents a front elevation of the lining attachment and parts adjacent thereto;

Fig. 4 represents a detail elevation of certain of the parts moved to another position from that shown in Fig. 3;

Fig. 5 represents a vertical section taken in the 40 plane of the line V—V of Fig. 4, looking in the direction of the arrows;

Fig. 6 represents an inverted plan view taken in the plane of the line VI—VI of Fig. 4, looking in the direction of the arrows;

45 Fig. 7 represents a detail of the removable scale showing the reverse side from that shown in Figs. 3 and 4;

Fig. 8 represents a side elevation of my improved cutter;

50 Fig. 9 represents a front elevation of the same; Fig. 10 represents a rear elevation of the same; and

Figs. 11 to 19 inclusive, represent detail front elevations, on still a larger scale, of the cutting 55 end of a series of cutters, each arranged to cut a plurality of grooves of various widths and depths.

My invention may be conveniently applied to a machine of the general type, such as that shown, 60 described and claimed in Letters Patent No.

641,470 granted to Royle dated June 16, 1900, and hence specific detail of the machine itself will be omitted as its mechanism and operation is well known in the art.

The table which supports the plate to be 5 operated upon is denoted by 1, and the clamp, vertically movable with respect to the table 1, by 2. The table and clamp are mounted to carry the plate to be operated upon into and out of engagement with the beveling cutters 3 fixed in a head 4 mounted on a spindle 5 journaled in a bearing 6 and driven by means of a band pulley 7 from a suitable source of power (not shown). A bracket 8 is secured to the bearing 6 by bolts 9 and serves as a support for a turret having 10 a plurality of lining cutters mounted on the bracket in rotary adjustment, so as to bring any 15 one of the several cutters into operative position at pleasure.

The turret consists in the present instance of a hub 10 provided with a plurality of arms 11, 12, 13 radiating therefrom, the outer ends of the arms being turned at an angle to their inner portions so as to occupy positions substantially at right 20 angles to the radii of their mounting. 25

The hub 10 is positioned to rotate on a vertically disposed stud 14 fixed in the bracket 8. The outer end of each of the arms 11, 12, 13 is provided with a socket 15 within which is fixed a sleeve 16 by means of a set screw 17 (see Fig. 2). 30

This sleeve 16 is exteriorly screw threaded at 17 to receive one end of a micrometer gauge 18, while the other end of the gauge has a screw 35 threaded engagement at 19 with a conical bushing 20, in which is journaled a spindle 21 of a swinging cutter support 22.

The spindle 21 has a conical surface 23 which coacts with a correspondingly interiorly tapered seat 24 in one end of the bushing 20. The other or outer end of the bushing is provided with a 40 tapered interior seat 25 disposed in the opposite direction from the seat 24 and arranged to receive a conical follower 26 keyed at 27 to rotate with the spindle 21. This follower 26 is yieldingly held in position by means of a spring 28 housed in a 45 cap 29 having a screw threaded engagement with the outer end of a bolt 30 longitudinally disposed in the spindle 21. This cap 29 is locked in its position on the bolt 30 by a nut 31.

The bushing 20 is mounted to slide longitudinally in the sleeve 16 and is prevented from turning therein by a tongue and groove connection therebetween, of which the tongue 32 is fixed in the sleeve 16 and the longitudinal groove 33 is formed in the bushing 20. Thus, it will be seen 55 that, while the bushing 20 may be moved longitudinally by the rotation of the micrometer gauge 18 on the sleeve 16 to give lateral adjustment to the cutter support 22, the swinging movement is controlled by the frictional contact of the coni- 60

cal interior seats of the bushing and the tapered portion of the spindle 21 and conical follower keyed on the spindle.

This construction of the cutter support and 5 mounting insures the steadiness of the cutter when in action and conveniently retains the support in such swinging adjustment as it may be placed in by the operator when the cutter is out of engagement with the plate.

10 In order to register the lateral movement of the cutter support 22 by means of the micrometer gauge 18, I provide a collar 34 having a frictional engagement with the reduced end 35 of the gauge 18, which collar 34 is provided with 15 graduations 36 arranged to register with a zero point 37 fixed on the arm of the turret carrying the gauge (see Fig. 1).

The cutter support 22 is oscillated by means of a lever 38 pivoted on a stud 39 carried by an 20 ear 40 extending upwardly from the turret arm and having a spur gear 41 arranged to mesh with a similar gear 42 fixed to the spindle 21 by means of screws 43. The free end of the lever 38 is provided with a thumb piece 44 for the convenience of the operator in pressing down the 25 cutter to its work.

The cutter 45 is secured to its support by means of a slanting groove 46 arranged to receive an offset 47 on the cutter. This offset 47 30 extends longitudinally along one side of the cutter and permits the cutter to slide longitudinally along the groove in the support 22 in an oblique direction toward and away from the plate 48 to be operated upon so as to bring the 35 point only of the cutter into engagement with the plate.

The cutter is held in its position on the support by means of a cheek piece 49, the upper end of which has an offset 50 on its inner face to 40 hold the body of the cheek piece away from the adjacent portion of the support 22, and at its lower end the cheek piece is provided with a V-shaped groove 51 adapted to engage the outer face of the cutter 45 and a portion of the back 45 of the cutter. The cheek piece 49 is clamped to the support 22 by means of a stud 52 fixed therein and having its outer end screw threaded to receive a nut 53.

The depth of the cut is regulated to the greatest 50 degree of accuracy by means of a presser foot 54 disposed in close proximity to the cutting point of the cutter 45. This presser foot 54 is fixed to a plunger 55 arranged to slide vertically in the support 22 and is prevented from turning 55 by means of a guide pin 56 mounted to slide in a hole 57 in the bottom of the support 22. The presser foot 54 is yieldingly held at the limit of its upward movement by a spring 58, one end of which rests on the bottom wall of a recess 59 formed in the support, while the upper end engages a collar 60 pinned to the plunger 55.

The position of the presser foot 54 with respect to the plate 48 is controlled by a member 61 having a screw threaded engagement with a rotatable shaft 62, one end 63 of which is mounted in the support 22 and the other end 64 journaled in an arm 65 extending upwardly from the support 22.

A thumb nut 66 is pinned at 67 to the end 64 70 of the shaft 62 so that by rotating the thumb nut the shaft will move the member 61 longitudinally thereon. This member is provided on its lower face with a longitudinal channel 68, the bottom 69 of which is inclined throughout its 75 length and arranged to receive the upper end

of the plunger 55 of the presser foot 54 so that the longitudinal movement of the member on the shaft will move the plunger and presser foot in a vertical direction against the tension of the spring 58.

The member 61 has scribed on its outer surface a zero point 70 which may be secured in position on its shaft 62 by means of a thumb screw 71 having a screw threaded engagement with the arm 65 and arranged to impinge against the portion of the shaft which is journaled in the arm.

In order to accurately predetermine the position of the presser foot with respect to the point of the cutter, I provide a gauge 72 in the form 15 of a flat plate having a series of graduations 73, 74, 75, 76 scribed on its faces, which graduations are designed to register with the zero point 70 on the member 61.

This gauge 72 is removably mounted in vertically disposed recesses 77, 78 formed in a carrier 79 mounted to slide on a rod 80 having one end 81 fixed in the support 22 and the other end 82 carried by the arm 65. The carrier 79 is locked in position on the rod 80 by means of a thumb screw 83 having a threaded engagement with the carrier and arranged to impinge upon the rod 80. The gauge 72 is frictionally held in the recesses 77, 78 of the carrier 79 by means of a flat spring 84 housed in the recess 77 and arranged to frictionally contact with one edge of the gauge.

The cutter 45 is designed to cut a groove in the plate, which groove will have a flat bottom and outwardly inclined side walls. The cutting point of the cutter has a horizontally straight bottom cutting edge 85 and side cutting edges 86, 87 inclined upwardly and outwardly from the bottom cutting edge. The side cutting edges 86, 87 are formed with substantially the same degree or angle of inclination with respect to the bottom cutting edge, so that in operation the width of the groove is governed by the depth the bottom cutting edge 85 is allowed to pierce the surface of the plate.

In practice, the maximum depth of a groove 45 is about one sixty-fourth of an inch, and in order not to exceed this condition and still produce different widths of grooves by increasing the depth of cut, I provide a series of cutters, each designed to cut grooves of varying widths, 50 the maximum width of which grooves is accomplished when the cutter has reached a depth of one sixty-fourth of an inch in the surface of the plate.

The cutting faces of the series of cutters are 55 shown on an enlarged scale in Figs. 11 to 19 inclusive, and are inscribed with the legends I⁰—I¹—I²—I³—I⁴—I⁵—I⁶—I⁷—I⁸ to designate the particular widths of grooves the cutters will cut in the plate.

The cutter having the legend I⁰, shown in Fig. 11, may be operated to cut grooves having its initial cut in the form of a scratch of very narrow width and slight depth to a groove having a depth of at least one sixty-fourth of an 65 inch and a width substantially equal to the depth.

The cutter I¹, shown in Fig. 12, is designed to cut an initial groove equal to the maximum width of groove cut by the cutter I⁰ and may be 70 operated to cut grooves increasing in width until the cutter has reached its maximum depth of one sixty-fourth of an inch.

Likewise, the cutter I², shown in Fig. 13, has an initial cut equal to the maximum cut of the 75

cutter I^1 , and the maximum width cut is controlled by the depth of the cutter entering the surface of the plate to the limit of one sixtieth of an inch.

5 The cutter I^3 also follows the cutter I^2 to increase the width of groove, while the cutters $I^4-I^5-I^6-I^7-I^8$ follow consecutively to provide cutters for progressively wider grooves than that cut by the cutters $I^0-I^1-I^2-I^3$, but all the cutters are limited to the same uniform depth to produce its maximum width of groove.

10 To facilitate ease in operation and to indicate to the operator the cutter in use, as well as to position the presser foot with respect to the cutter, provide the gauge plate 72 above the graduations, with the characters corresponding to the characters on the cutters.

15 In the present instance, the series of graduations 73 on the gauge plate 72 are numbered 0, 15, 30, and 45 and the characters $I^0-I^1-I^2-I^3$ disposed, respectively, above the numerals. The series of graduations 74 are designated by the numerals 45, 60, 75, and 90 and register with the characters $I^3-I^4-I^5-I^6$ respectively. The series 20 of graduations 75 are inscribed with the numerals 90, 105, 120, and 135, and the characters $I^6-I^7-I^8$ register with the numerals 90, 105, and 120 respectively. The series of graduations 76 carry the numerals 135, 150, 160, and 180 and may be 25 used to register the cut of any one of the cutters shown and described or any similar lining cutter.

30 As previously described, the zero point 79 on the member 61 registers with the graduations on the gauge plate 72, and by reason of the inclined bottom 69 of the channel 68 in the member 61 and its coaction with the plunger 55 of the presser foot, any longitudinal movement of the member 61 on its shaft 62 will cause the zero point 79 to change its position with respect to the graduations and also control the position of the presser foot with respect to the point of the cutter.

35 Assuming that the cutter I^7 is disposed in the support 22, as shown in Fig. 3, and it is desired to increase the width of the groove to be cut, the shaft 62 is manipulated by the thumb nut 66, so that the member 61 will be moved to the right. In this movement the inclined bottom 69 was brought to another position with respect to the plunger, and the plunger urged upwardly by the 40 tension of the spring 58 between the collar 60 and arm 22. This upward movement of the plunger carried the presser foot 54 away from the point of the cutter, thereby allowing the cutter to cut deeper into the surface of the plate.

45 By the cutter entering further into the surface of the plate, larger cutting surfaces with the inclined side cutting edges 86, 87, in addition to the bottom cutting edge 85 were brought into use, thus widening the distance across the groove.

50 To reduce the width of groove to be cut in the plate, the thumb nut 66 is manipulated to move the member 61 to the left, so that the inclined bottom 69 of the channel 68 will press the plunger 55 downwardly against the tension of the spring 58 and the presser foot 54 closer to the point of the cutter, thereby limiting the depth the flat bottom cutting edge 85 and the inclined side cutting edges 86, 87 may pierce the 55 surface of the plate. Thus, the movement of the member 61 regulates the width and depth of the groove to be cut, and the position of the member with respect to the gauge is readily visible to the operator so that he may accurately 60 determine the position of the presser foot with

respect to the cutter so as to cut a wider or narrower groove.

5 From the foregoing, it will be seen that any number of grooves of a predetermined width or of different widths may be cut on a plate or a number of plates more accurately with a single cutter, and the pressure applied by the operator on the thumb piece 44 to rock the lever 38 and the supporting arm 22 to actuate the cutter to cut the grooves cannot cause the cutter to pierce the surface of the plate any deeper than the presser foot will allow by its contact with the plate.

10 By this construction, the cutter may be brought into and out of operation by a short oscillating movement of the lever, and the cutter, when disposed in its operative position, is located almost beneath its center of oscillation so that any liability of the cutter to chatter is obviated.

15 It will be understood that various changes may 20 be resorted to in the form, construction and arrangement of the several parts without departing from the spirit and scope of my invention; and hence I do not intend to be limited to the details herein shown and described, except as they may 25 be included in the claims.

What I claim is:

1. In combination, a lining cutter support, a cutter thereon, a plate carrier movable to bring the plate into and out of engagement with the cutter, means in the support arranged to be brought into contact with the plate for limiting the movement of the cutter into the plate, a device arranged to be reciprocated in the support for controlling the movement of said means, a removable gauge carried by the support, and a zero line on said device coacting with the gauge for registering the position of the means in the support with respect to the depth the cutter may 30 cut into the plate.

2. In combination, a lining cutter support, a cutter thereon, a plate carrier movable to bring the plate into and out of engagement with the cutter, means in the support arranged to be brought into contact with the plate for limiting the movement of the cutter into the plate, a device arranged to be reciprocated in the support for controlling the movement of said means, a carrier mounted in the support, and a gauge 45 therein arranged to coact with said device for registering the position of the means in the support with respect to the depth the cutter may 50 cut into the plate.

3. In combination, a lining cutter support, a cutter thereon, a plate carrier movable to bring the plate into and out of engagement with the cutter, means in the support arranged to be brought into contact with the plate for limiting the movement of the cutter into the plate, a device arranged to be reciprocated in the support for controlling the movement of said means, a carrier mounted in the support, and a gauge 55 removably secured therein and arranged to coact with said device for registering the position of the means in the support with respect to the depth the cutter may 60 cut into the plate.

4. In combination, a lining cutter support, a cutter thereon, a plate carrier movable to bring the plate into and out of engagement with the cutter, means in the support arranged to be 70 brought into contact with the plate for limiting the movement of the cutter into the plate, a device arranged to be reciprocated in the support for controlling the movement of said means, a carrier laterally adjustable in the support, and 75

- a gauge therein arranged to coact with said device for registering the position of the means in the support with respect to the depth the cutter may cut into the plate.
5. In combination, a lining cutter support, a cutter thereon, a plate carrier movable to bring the plate into and out of engagement with the cutter, means in the support arranged to be brought into contact with the plate for limiting the movement of the cutter into the plate, a device arranged to be reciprocated in the support for controlling the movement of said means, a carrier laterally adjustable in the support, and a gauge removably secured therein and arranged to coact with said device for registering the position of the means in the support with respect to the cutter.
6. The combination with a movable plate carrier, of an arm, a lining cutter, an oscillating support therefor having a spindle mounted in said arm, said support being adapted to rock on one side of the arm, a gear fast on the spindle, and a lever pivoted to oscillate on the other side of the arm in close proximity to the vertical plane of movement of the support and having a gear meshing with the gear on the spindle, whereby the movement of the lever will actuate the gears and rock the cutter support on the arm.
7. The combination with a movable plate carrier, of an arm, a lining cutter, an oscillating support therefor having a spindle in said arm, a micrometer adjusting device for moving said spindle in the arm and setting the cutter laterally with respect to the movement of the plate, a gear fast on the spindle, a lever pivoted to oscillate on the arm and having a gear meshing with the gear on the spindle, whereby the movement of the lever will actuate the gears and rock the cutter support on the arm.
8. The combination with a movable plate carrier, of an arm, a lining cutter, a support therefor having a spindle in said arm, a micrometer adjusting device for moving said spindle in the arm and setting the cutter laterally with respect to the movement of the plate, a gauge rotatably mounted on said micrometer adjusting device, a zero line on the arm for registering the movement of said gauge, a gear fast on the spindle, a lever pivoted on the arm and having a gear meshing with the gear on the spindle, whereby the movement of the lever will actuate the gears and rock the cutter support on the arm.
9. The combination with a movable plate carrier, of an arm, a conical bushing secured in said arm, a lining cutter support having a spindle mounted in said bushing, a conical follower carried by and movable on said spindle, means on the spindle for adjusting the follower in the bushing, a gear fast on the spindle, a lever pivoted on the arm and having a gear meshing with the gear on the spindle, whereby the movement of the lever will actuate the gears and rock the cutter support on the arm.
10. The combination with a movable plate carrier, of an arm, a conical bushing secured in said arm, a lining cutter support having a spindle mounted in said bushing, a conical follower carried by and movable on said spindle, yielding means on the spindle for adjusting the friction of the follower in the bushing, a gear fast on the spindle, a lever pivoted on the arm and having a gear meshing with the gear on the spindle, whereby the movement of the lever will actuate the gears and rock the cutter support on the arm.
11. In combination, an oscillating lining cutter support, a cutter thereon, a plate carrier movable to bring the plate into and out of engagement with the cutter, and means vertically adjustable in the support and spaced apart in advance of the cutter, said means being arranged to be brought into contact with the plate for predetermining the depth of cut to be made and limiting the movement of the cutter into the plate.
12. In combination, an oscillating lining cutter support, a cutter thereon, a plate carrier movable to bring the plate into and out of engagement with the cutter, means in the support spaced apart in advance of the cutter, said means being arranged to be brought into contact with the plate for predetermining the depth of cut to be made and limiting the movement of the cutter in the plate, and a device in the support having an inclined surface for controlling the position of said means in the support.
13. In combination, an oscillating lining cutter support, a cutter thereon, a plate carrier movable to bring the plate into and out of engagement with the cutter, means in the support spaced apart in advance of the cutter, said means being arranged to be brought into contact with the plate for predetermining the depth of cut to be made and limiting the movement of the cutter in the plate, and a device arranged to be reciprocated in the support and having a horizontally inclined surface for controlling the position of said means in the support.
14. In combination, an oscillating lining cutter support, a cutter thereon, a plate carrier movable to bring the plate into and out of engagement with the cutter, means in the support spaced apart in advance of the cutter, said means being arranged to be brought into contact with the plate for predetermining the depth of cut to be made and limiting the movement of the cutter in the plate, a device arranged to be reciprocated in the support and having a horizontally inclined surface for controlling the position of said means in the support, and a gauge coacting with said device for registering the position of the means in the support with respect to the depth the cutter may cut into the plate.
15. In combination, an oscillating lining cutter support, a cutter thereon, a plate carrier movable to bring the plate into and out of engagement with the cutter, means in the support spaced apart in advance of the cutter, said means being arranged to be brought into contact with the plate for predetermining the depth of cut to be made and limiting the movement of the cutter in the plate, a device arranged to be reciprocated in the support and having a horizontally inclined surface for controlling the position of said means in the support, a gauge coacting with said device for registering the position of the means in the support with respect to the depth the cutter may cut into the plate, and a zero line on the device coacting with said gauge for registering the position of the means in the support.
